ABSTRACT OF THE DISCLOSURE

Apparatus for horizontally aligning railroad tracks comprises a frame having two pairs of teeth spaced-apart in the direction of the track. Each pair of teeth has angled rail engaging surfaces, the surfaces of one pair facing outwardly so as to engage the inner faces of the rails and the surfaces of the other pair facing inwardly so as to engage the outer faces of the rails. Means are provided to tilt the frame so that one pair of surfaces engages the rails before the other pair.

BACKGROUND OF THE INVENTION

This invention relates to apparatus for railway track maintenance operations, and in particular to a liner assembly for horizontally aligning track without affecting its gauge.

As is well known in the art, railway tracks undergo periodic operations for maintaining the track correctly positioned in both the vertical and the horizontal planes; such maintenance operations are called "surfacing" for the correction of bumps and depressions, and "alignment" for the straightening of bends in the track caused by lateral slipping thereof. These maintenance operations are generally performed by a track maintenance machine which rides along the track and corrects it incrementally in a step-by-step manner.

Track alignment operations are carried out by track "liners" which clamp onto both rails and "throw" the track laterally to a corrected position by the action of hydraulic jacks.

Until now, difficulty has been experienced with use of clamping devices due to the fact that the spacing of the rails of a track varies from spot to spot and is deliberately varied in curved sections—sometimes by as much as 1½ inches—to provide for better train wheel motion in curves. It is, of course, necessary to maintain the required rail spacing whilst conducting an "alignment" operation and this presents problems.

Prior clamping devices were generally in the form of two sets of articulated jaws mounted on a transverse frame member with a predetermined factor of "sloppiness" such that the distance between them could be varied slightly to correspond approximately to the rail spacing of the track to be clamped. However, the general tendency was to bend one of the rails slightly to accommodate for the variation in rail spacing.

SUMMARY OF THE INVENTION

According to the present invention there is provided, for mounting on a track maintenance machine, a liner assembly comprising a frame; means for mounting said frame on said machine including means for displacing the frame generally vertically and means for displacing the frame laterally of said machine; a pair of inner teeth depending from said frame in a fixed transversely spaced apart relationship on one side of said frame, each inner tooth presenting a rail engaging surface which is arranged to project at a wedging angle towards the inner

2

edge of a rail; and a pair of outer teeth depending from said frame in a fixed transversely spaced apart relationship on the other side of said frame, each outer tooth presenting a rail engaging surface which is arranged to project at a wedging angle towards the outer edge of a rail; said frame being free to rock about a horizontal axis transverse to said track, thereby, upon lowering of said frame structure into engagement with said track, to allow said frame to assume an angular position in which the mean value of the two distances between the rail engaging regions of the engaging surfaces of said pairs of inner and outer teeth equals the spacing of the rails of the track being clamped.

Stated differently, we provide two pairs of generally downwardly projecting rail engaging surfaces which are disposed in a generally rectangular configuration so as to make wedging contact with the four edges of a pair of rails. One pair of surfaces engages the inner edges of the rails at one place and the other engages the outer edges of the rails a short distance away. Although the distances between the surfaces cannot be changed, the distances between the two lines of contact of each pair of surfaces can be varied by simply shifting these lines on the respective surfaces provided both surfaces at one side are convergent and both surfaces at the other side of the frame structure are divergent.

Consequently, it is now possible to rigidly secure these teeth to the frame of the assembly; and by allowing relative displacement of these teeth in opposite vertical directions, as by allowing free rocking motion of the frame structure transversely of the track, the mean value of the distances between the opposite lines of contact will automatically become equal to the rail spacing upon lowering of the assembly onto the rails.

In an embodiment of the present invention there is provided a liner assembly wherein a resiliently suspended flanged wheel is provided under each end of the assembly so that when the track maintenance vehicle moves these wheels roll on the track and prevent accidental wedge engagement of the clamping means with the rails and keep the assembly properly centered on the rails.

Moreover we preferably provide an additional pair of teeth on at least one of the transverse frame members, so that for a majority of track where the rail spacing is equivalent to the track gauge both edges of each rail are engaged by the teeth of the same transverse frame member.

Furthermore, a liner assembly in accordance with the present invention preferably includes means in the form of hydraulic jacks to move the assembly relative to the track maintenance vehicle.

BRIEF DESCRIPTION OF DRAWING

In drawings which illustrate the basic principle, and a preferred embodiment of the invention,

FIG. 1 is a schematic representation in perspective of a liner assembly clamping means in accordance with this invention,

FIGS. 2 and 3 are front and end views of the schematic representation of FIG. 1 in a first angular position,

FIGS. 4 and 5 are front and end views of the schematic representation of FIG. 1 in a second angular position,

FIG. 6 is an elevational view of a liner assembly in accordance with this invention, and

FIG. 7 is a cross-sectional view of the liner assembly shown in FIG. 6, taken along line 7—7.

DESCRIPTION OF THE PREFERRED EMBODIMENTS

It should be understood that FIGS. 1 to 5 which are intended to facilitate understanding of the principle of

clamping means in accordance with this invention have been considerably exaggerated and simplified.

In FIG. 1 a section of a railway track is shown and referred to generally by reference numeral 1. Element 2 represents a structure to which it is desired to clamp the rails of track 1 by means of a clamping device 3.

The clamping device 3 consists of a generally rectangular frame structure 4 provided with front and rear wedge means 5 and 6. Each wedge means has a pair of downwardly projecting teeth 7a, 7b, 8a, 8b. The teeth 7a, 7b of the front wedge means 5 present a pair of rail engaging surfaces 9 and 10 which face generally outwardly of the liner assembly and project at a wedging angle "α" towards the inner edges of the rails. The corresponding rail engaging surfaces 11 and 12 of the teeth 8a, 8b of the rear wedge means 6 face inwardly of the rails and project towards the outer edges of the rails at a wedging angle which is preferably equal to angle "α".

As can be seen from FIGS. 2 and 4, the rail engaging surfaces 9, 11 and 10, 12, when in contact with the rails, define V-shaped formations 14a, 14b whose apices are directly above the rails. By comparison of FIGS. 2 and 4 it will be seen that the distance between the apices of the V-shaped formations 14a, 14b, which corresponds to the rail spacing, can be varied from a value d_1 to a value of d_2 by tilting the frame 4 from the positions of FIG. 3 to that of FIG. 5. Thus, by simply adjusting the angular position of the frame structure 4 about a horizontal transverse axis or, in more general terms, by adjusting the relative vertical position of the wedge means 5 and 6, the teeth 7a, 7b, 8a, 8b which are fixedly spaced apart relative to one another, can positively engage the inner and outer edges of both rails for any value of rail spacing between d_1 and d_2 . This accommodation for variation of rail spacing without changing the distance between the teeth at each side of the frame 4, is made possible by the fact that the rail engaging surfaces 9 and 10 are convergent while the rail engaging surfaces 11 and 12 are divergent, which enables adjustment of the position on each rail engaging surface 9, 10, 11, 12 of the line of contact thereof with a rail edge. In fact when all four teeth are in contact with the rail the mean value of the distance between the lines of contact of teeth 7a and 7b and of the distance between the lines of contact of teeth 8a and 8b equals the mean spacing of the rails of the track. This adjustment takes place automatically if the frame structure 4 is free to pivot as at 13.

In addition to teeth 9, 10, 11 and 12 two extra teeth 15 and 16 can be mounted opposite teeth 11 and 12 and shown in chain lines in FIG. 2. These extra teeth are spaced apart from teeth 11 and 12 so that they engage the inner edges of the rails only when the frame 4 is tilted to the maximum rearward angular position illustrated in FIG. 3, i.e. the position of the frame which corresponds to the track gauge d_1 . Similarly the front wedge means 5 can be provided with two extra teeth 17 and 18 which would contact the outer edges of the rails when the frame 7 is in the maximum forward angular position as shown in FIG. 5, i.e. that corresponds to the widest possible rail spacing d_2 .

Referring now to FIGS. 6 and 7 there is represented a liner assembly 20 in accordance with this invention which is mounted on a track maintenance vehicle represented by frame member 21. The liner assembly 20 comprises clamping means 23, and means 22 for displacing the clamping means 23 on the vehicle towards and away from the track 1 to cause engagement and disengagement of the clamping means with the rails of the track 1. The liner assembly 20 also comprises reciprocatting means 24 which is adapted to shift the clamping means 23 sideways relative to the vehicle.

The clamping means 23 which is adapted to confine the rails 1 against lateral displacement relative to one another comprises a frame structure 25 and wedge means 26 depending from each transversely extending side of the

frame structure 25. The frame structure 25 is a generally rectangular assembly which essentially comprises two transversely extending frame members 27 and 28 which are rigidly interconnected in a parallel spaced apart relationship, and from which depend the wedge means 26. The wedge means 26a of the frame member 27 has inner teeth 30 and 31 which are disposed inwardly of the rails of track 1, while the wedge means 26b of the frame member 28 has outer teeth 32 and 33 which are disposed outwardly of the rails of the track 1. These teeth should be sufficient in most cases but as was mentioned hereinbefore in connection with FIGS. 1 to 5 additional teeth 30', 31', 32' and 33' could be added which would contact the rails only in the extreme angular positions of the frame structure 25 and therefore only at minimum and maximum rail spacing.

The means 22 which allows for vertical displacement of the liner assembly 20 comprises a pair of hydraulic jacks 40 each of which is connected at the upper end to a bracket 41 by means of a spherical bearing 42, and at the lower end to a coupling 43 which has a spherical bearing connection 44 with the jack 40 and also allows pivotal movement of the frame structure 25 about pivot pin 45 of a pivotal connection 46.

The reciprocatting means 24 which causes lateral displacement of the clamping means 23 comprises a further hydraulic jack 50 whose cylinder 51 is rigidly secured to the frame structure 25, and whose piston rods 52 and 53 are linked to the frame of the vehicle. The piston rods 52 and 53 are connected to arms 54 and 55 which in turn are pivotally connected to brackets 56 and 57 of the frame of the track maintenance vehicle.

At each end of the liner assembly the frame structure 25 is provided with a flanged wheel 60 and 61. Each flanged wheel is rotatably mounted on a vertically displaceably sub-frame 62 which is in sliding engagement with pins 63 of the frame structure 25. A pair of coil springs 64 are provided between the top surface of the sub-frame 62 and the lower surface of the member of the frame structure 25 that holds the pins 63. The coil springs 64, which in fact are compressed between the rails and the frame structure 25 in the position shown in FIG. 7, tend to separate the frame structure 25 from the sub-frame 62 in the vertical direction. This arrangement of flanged wheels mounted on springs has three functions namely centering the frame structure 25 with the rails of the track 1 during movement of the vehicle, preventing accidental positive engagement of the teeth with the rails during movement of the vehicle, and causing the front teeth 30 and 31 to be the first ones to engage the rails upon initial lowering of the liner assembly towards the rails.

The first and the second functions greatly simplify the control means for the operation of the liner assembly. In fact with the flanges on the wheels 60, 61 it is no longer necessary to use rail seeking means to control the lateral position of the frame structure 25 as the vehicle moves from one track section to another for alignment; and with the springs which maintain the clamping means slightly above the rails when the pressure in jacks 40 is reduced, e.g. during motion of the vehicle, there is no need for release means which are required when articulated jaws are used, for unclamping the clamping means after each aligning operation. The third function is caused by the fact that the pivot connection 46 of the jack 40 with the frame structure 25 is in a vertical plane which is forward of the vertical plane that contains the axis of the wheels 60, 61. Thus downward movement of the coupling 43 tilts the frame structure 25 forwardly about the axes of wheels 60 and 61 and causes the front teeth 30 and 31 to contact the inner edges of the rails. After contact of teeth 30, 31, further downward motion of coupling 43 pivots the frame structure 25 in the opposite direction about the front teeth 30 and 31 until teeth 32 and 33 contact the outer edges of the rails of track 1.

Thus it will be seen a liner assembly is provided which incorporates at least four rail engaging surfaces for providing a four point wedge engagement with a pair of rails, in which the wedge means are part of a sturdy generally rectangular frame structure which has no movable parts and yet which can accommodate for normal variation in rail spacing.

What we claim as our invention is:

1. For use on a railway maintenance machine a liner assembly for horizontally aligning the rails of a track comprising a frame; means for mounting said frame on said machine including means for displacing the frame generally vertically and means for displacing the frame laterally of said machine; a pair of inner teeth depending from said frame in a fixed transversely spaced apart relationship on one side of said frame, each inner tooth presenting a rail engaging surface which is arranged to project at a wedging angle towards the inner edge of a rail; and a pair of outer teeth depending from said frame in a fixed transversely spaced apart relationship on the other side of said frame, each outer tooth presenting a rail engaging surface which is arranged to project at a wedging angle towards the outer edge of a rail; said frame being free to rock about a horizontal axis transverse to said track, thereby, upon lowering of said frame structure into engagement with said track, to allow said frame to assume an angular position in which the mean value of the two distances between the rail engaging regions of the engaging surfaces of said pairs of inner and outer teeth equals the spacing of the rails of the track being clamped.

2. A liner assembly as defined in claim 1 additionally comprising a flanged wheel mounted at each end of

said frame and adapted to roll on said rails thereby to cause continuous centering of said frame with respect to the track.

5 3. A liner assembly as defined in claim 2 wherein said wheels are spring suspended onto said frame so as to urge said teeth away from the rails.

10 4. A liner assembly as defined in claim 1 wherein on at least one side of said frame a second pair of teeth is provided which presents a second pair of engaging surfaces adapted to co-operate with the first mentioned pair thereof to engage the inner and outer edges of the rails of a track having a predetermined rail spacing.

15 5. A liner assembly as defined in claim 1 wherein the rocking axis is parallel to, and located between, two vertical planes containing said teeth.

20 6. A liner assembly according to claim 5 comprising a rail engaging wheel at each end of the frame which is resiliently mounted on the frame to urge the teeth away from the rails, said rocking axis being coaxial with the rotational axes of said wheel.

25 7. A liner assembly according to claim 6 wherein means is provided for moving the frame downwardly with respect to said wheel and said rails, said means acting in a vertical plane between said rocking axis and one pair of teeth whereby said one pair of teeth contacts the rails before the other pair of teeth.
